(57) **CLAIM**

The ornamental design for a facial cleansing mitten, as shown and described.

DESCRIPTION

FIG. 1 is a front perspective view of an example embodiment of a facial cleansing mitten of the present invention showing our new design;

FIG. 2 is a front view thereof;

FIG. 3 is a rear view;

FIG. 4 is a side view thereof;

FIG. 5 is another side view rotated 180 degrees relative to FIG. 4;

FIG. 6 is a top view thereof;

FIG. 7 is a bottom view thereof;

FIG. 8 is an enlarged view of portion “8” shown in FIG. 6; and,

FIG. 9 is an enlarged view of portion “9” shown in FIG. 6. The stippling shown herein depicts a contrast in appearance. The evenly spaced broken lines depict portions of the facial cleansing mitten and form no part of the claimed design. The dot-dash broken lines depict a boundary line, and form no part of the claimed design. The dot-dot-dash broken lines shown in FIGS. 6, 8, and 9 are for the purpose of depicting enlarged view indicators and form no part of the claimed design.
